UNITED STATES PATENT OFFICE.

CHARLES MIRMILLO, OF OAKLAND, CALIFORNIA.

GUN.

1,272,293.

Specification of Letters Patent.

Patented July 9, 1918.

Application filed October 24, 1916. Serial No. 127,361.

To all whom it may concern:

Be it known that I, CHARLES MIRMILLO, citizen of the United States, residing at Oakland, in the county of Alameda and State 5 of California, have invented certain new and useful Improvements in Guns, of which the following is a specification.

This invention relates to improvements in guns and more particularly to a side loading 10 rifle which enables cartridges to be used with projectiles of any size.

The principal object of my invention is to improve the construction of the breech mechanism whereby the gun may be loaded 15 and the empty cartridge case ejected from the side and also to construct the breech mechanism that it may resist the powerful forces due to high explosive charges which are used with projectiles in cartridges.

20 Another object is to provide simple and effective recoil mechanism, an improved firing pin arrangement and shell ejecting means.

With these and other objects, which will 25 be brought forth in detail in the specification, in view, my invention consists in the novel arrangements and combination of parts herein described and more specifically pointed out in the appended claims.

30 Referring to the accompanying drawing forming a part of this specification,

Figure 1 is a view in side elevation of the improved gun.

Fig. 2 is a top plan view of the same.

35 Fig. 3 is a longitudinal sectional view through the breech end of the gun.

Fig. 4 is a view in horizontal section of the breech at the loading chamber.

40 Fig. 5 is a view in rear elevation of the breech block.

Fig. 6 is a view in rear elevation of the breech block with a bearing plate removed.

Fig. 7 is a view in section through the rear 45 portion of the gun showing the breech block in position.

Fig. 8 is a view in section through the barrel at the loading slot showing the means for withdrawing the shell from the firing chamber.

50 Fig. 9 is a view in side elevation of the cartridge used in the gun.

Fig. 10 is a view in section through the base end of the cartridge case.

Referring to the corresponding parts of 55 the several views by the same numerals of reference, 1 denotes the gun barrel having

rifled bore 2 and for convenience of manufacture this barrel is made in two sections, the rear section being indicated by 2'. These sections are in screw threaded engagement 60 with the yoke member 3, which has a longitudinal extending rib 4, which in turn is provided with laterally extending guides 5. These guides are slidably mounted in suitable ways 6 in the upper part of the recoil 65 chamber casing 7. This casing is held in a U-shaped yoke member 8 having trunnions 9 by which the gun is pivotally mounted in a suitable carriage, a portion of which is indicated at 10.

70 The recoil chamber denoted by 11, is cylindrical in outline and has the removable caps 12 and 13 at each end thereof. Within this chamber is a suitable compression spring 14 abutting at one end against the cap 12 and 75 having on its other end a head 15. In the upper side of the chamber casing is a longitudinally disposed slot 16 and through this slot extends an arm 17 formed on the lower portion of the holding member 3. This arm 80 contacts with the head 15 so that when a gun is fired the recoil causes the arm 17 to move rearwardly in slot 16 against the compression spring 14.

85 The breech block is denoted generally by 80 and consists of the cylindrical portions 18 and 19, the former being smooth on its outer surface, while the latter is provided with the segmental screw threads 20. These screw threads are longitudinally slidable 90 in the slots 21 (Fig. 7,) whereby the breech block may be locked by a fractional turn. On the rear of the screw threaded portion 19, is provided an enlarged collar 23 having an annular recess 24 upon which is revolvably 95 mounted the ring 25. This ring being provided on one side with a hub 26 in which is keyed a rod 27. This rod on the rear portion is provided with a toothed rack 28 arranged to engage a toothed pinion 29, keyed 100 to shaft 30, which shaft is revolvably mounted in a yoke 31 attached to the rear end of the gun barrel. Upon both sides of this shaft are attached operating wheels 32 having one or more handles 33, as shown in Figs. 105

1 and 7. The portion 7 of the gun carriage is provided with a longitudinal opening 34 in which the rod 27 is adapted to slide. This rod and opening being of sufficient length to provide a guide whereby the breech block 110 is held in parallel relation to its bore while being moved in or out. Member 25 is held

in the grooved shoulder 24 by means of the ring 36, this ring having a handle 37, enabling the breech block to be turned in the bore to lock it in position.

5 The shell chamber is denoted by 38, the ejection chamber by 39, and 40 denotes a side outlet from the latter chamber through which the shell is ejected after firing. Opening 40 is of the same length as the cartridge and diametrically opposite this opening on the opposite side of the gun is pivotally mounted a lever 40' having a segmental arm 42² adapted to extend through a slot 42' into the chamber 39. By means of this 10 arm a shell lying within the chamber 38 may be forced out through outlet 40.

The cartridge chamber 38 being in advance of the loading chamber 39, it is necessary to provide means for withdrawing the cartridge case after the projectile has been fired. This means consists of a block 41 slidably mounted on a rod 41' and moved longitudinally by means of the quick acting screw 42. This screw is pivotally mounted 20 in bearing plates 43 and 44 and within the latter has keyed to it the toothed beveled pinion 45. This pinion meshes with the corresponding toothed gear 46, having handles 47, by which it may be turned. Extending 25 from block 43 is a flat arm 48, this arm being bent inwardly to position within the slot 40 and on its inner end has a segmental curve 49, of a radius equal to the diameter of the cartridge shell back of the bead.

30 The firing mechanism consists of the rod 50 extending throughout the length of the portions 18 and 19 having a collar 51. The rear end of this rod is attached to a rack gear 52, which is rectangular in shape and 35 slidably mounted in a similarly shaped opening 52' in the blocks 53 and 53'. Between the collar 51 and rack member 52 is a circular hole 54 wherein is a spring 55, the forward end abutting against collar 51 and 40 the rear end abutted against the shoulders formed by the rectangular opening 52' and the circular hole 54. Pivotaly mounted at the rear end of the breech block is a shaft 60 having an operating wheel 61 with 45 suitable handles 62 and on this shaft is keyed a toothed gear adapted to mesh with the teeth of rack 52. Pivotaly mounted under this rack is a trigger arm 63, having a finger 64 which is adapted to enter a slot 65 formed 50 on the under side of the rack bar 52.

The cartridge consists of the brass shell casing 70 and projectile 71. The shell casing is screwed or welded to the cap end of the shell 75, which is provided with an annular bead 73. 74 denotes the priming cap, placed in a small block 75, which in turn is 55 removably inserted in 72.

The operation is as follows:

To load the gun the breech block 80 is 60 withdrawn by turning wheels 32, the block

41 being positioned as shown in Figs. 1 and 2. The cartridge is then inserted through slot 40 and the breech block run in by turning wheels 32 in the reverse direction, which causes the end of the portion 18 to push the 70 cartridge into the firing chamber 38. The firing pin is then set by turning the handle 62 so as to withdraw the rack 52 against spring 55 until the same is positioned so that the finger 64 of the trigger arm may be 75 inserted in slot 65, the breech block in the meantime being rotated by means of arm 37 so that the segmental screw portions engage and lock the block in position. Trigger 63 is then pulled in a clockwise direction 80 releasing finger 64 and permitting the rod 50 to be propelled forward under the action of spring 55. The end of the rod strikes the cap 75 and fires the charge within the cartridge shell. The breech block is then 85 unlocked and withdrawn by rotating handle 37. Block 40 is then moved rearwardly by means of the handles 47, and as the bead 73 of the cartridge shell is positioned back of the segmental end 49, the shell is pulled 90 back into the chamber 18. The block 40 is then moved into its forward position and the shell ejected by moving inwardly the lever arm 41. This leaves the various parts 95 of the gun in position for reloading.

While I have shown the preferred embodiment of my invention it may be understood that minor changes may be made in the details of the design without departing from the spirit thereof.

I claim as new and wish to cover by Letters Patent:—

1. A gun comprising a barrel having a firing chamber, a loading chamber back of said firing chamber and having a slot extending through the side of said barrel to permit a cartridge to be placed in said loading chamber, a breech block having a forward portion adapted to push said cartridge into said firing chamber, a block slidably mounted adjacent said slot and an arm extending from said block into said loading chamber, the end of said arm being adapted to contact with said cartridge and withdraw it from the firing chamber.

2. A gun comprising a barrel having a firing chamber, a loading chamber back of said firing chamber and having a slot extending through the side of said barrel to permit a cartridge to be placed in said loading chamber, a breech block having a forward portion adapted to push said cartridge into said firing chamber, a block slidably mounted adjacent said slot, an arm extending from said block into said loading chamber, the end of said arm being adapted to contact with said cartridge and withdraw it from the firing chamber, and an ejecting lever pivotally mounted on the outside of said barrel, and having a part adapted to be 130

extended into said loading chamber for ejecting the cartridge therefrom.

3. A gun comprising a barrel having a firing chamber forming a continuation of the bore of the barrel, a loading chamber having a slot extending through the side of said barrel to permit insertion and ejection of a cartridge, a breech block adapted to close said chambers and hold said cartridge in said firing chamber, a block slidably mounted on the outside of said barrel, an

arm extending from said block through said slot and normally lying at the rear end of the firing chamber and having a notched end adapted to engage the rear end of said cartridge, and operable means for moving said block axially of the loading chamber, whereby said arm will withdraw the cartridge from the firing chamber. 15

In testimony whereof I affix my signature. 20

CHARLES MIRMILLO.
